UNITED STATES PATENT OFFICE.

ALBERT OTTENHEIMER, OF STUTTGART, GERMANY, ASSIGNOR TO THE
OTTENHEIMER BROTHERS, OF NEW YORK, N. Y.

CORSET-CLASP.

SPECIFICATION forming part of Letters Patent No. 276,978, dated May 1, 1883.

Application filed February 12, 1883. (No model.)

To all whom it may concern:

Be it known that I, ALBERT OTTENHEIMER, of Stuttgart, in the Empire of Germany, have invented an Improvement in Corset-Clasps, of which the following is a specification.

In Letters Patent No. 181,970, I have shown two corset steels or busks laid one on the other and connected by hooks on one passing through mortises in the other, and a socket at the lower part of one receiving a tongue on the other busk or spring.

My present invention is an improvement on the aforesaid patent, and relates to the peculiar construction of the connecting devices hereinafter described, in combination with the busks.

In the drawings, Figure 1 is an elevation of the front part of a corset, with the busks clasped together. Fig. 2 is an edge view with the busks or steels separated from the fabric of the corset, the front busk being in section; and Fig. 3 is a vertical section of the hinged clasp and steels, in larger size.

The busks or steels *a* and *b* are of suitable width and thickness, and as one busk rests upon another, when clasped, the busks may be much thinner and more flexible than heretofore generally used, and they will not be so liable to break.

At the bottom end of the busk *a* there is a notch, and the busk is strengthened by a sheath, *d*, of thin sheet metal, surrounding and riveted to the busk, and this, also, is notched to correspond to the notch in the

busk. There are also one or more mortises or square holes passing through the busk, as seen at *e*.

Upon the lower end of the busk *b* there is a hook, *f*, made as a fixture, over which the notched end of the busk *a* is placed. There are also hinged clasps, each being made with a fixed joint-block, *i*, riveted upon the busk *b*, and at its outer end receiving the joint of the swinging clasp-piece *l*, having one long and the other a short end.

When the corset is to be clasped, the wearer passes the notched end over the hook *f*, the clasp-pieces *l* being swung out at right angles to the busk *b*, so that the same pass through the mortises in the busk *a* as that is pressed back against the busk *b*. The clasp-pieces *l* are then turned down against the surface of the busk *a*, and hold the same firmly. By the reverse movement the corset is unclasped, so as to be taken off.

I claim as my invention—

The busk *a*, having mortises through it and a notch at the lower end, in combination with the busk *b*, the hook *f*, attached thereto, and the joint-blocks *i*, and clasp-pieces *l*, hinged thereto, as and for the purposes set forth.

Signed by me this 27th day of January, A. D. 1883.

ALBERT OTTENHEIMER.
